UNITED STATES PATENT OFFICE.

HEINRICH TOUSSAINT, OF CASSEL-WILHELMSHOHE, GERMANY, ASSIGNOR TO SCHMIDT'SCHE HEISSDAMPF GESELLSCHAFT M. B. H., OF CASSEL-WILHELMSHOHE, GERMANY, A CORPORATION OF GERMANY.

SUPERHEATER FOR STEAM BOILERS.

Application filed May 17, 1920. Serial No. 332,200.

To all whom it may concern:

Be it known that I, HEINRICH TOUSSAINT, a citizen of Germany and resident of Cassel-Wilhelmshohe, Germany, have invented certain new and useful Improvements in Superheaters for Steam Boilers, of which the following is a specification.

This invention relates to superheaters embodying tubes arranged in the smoke flues of steam boilers, particularly cylindrical boilers such as ships' boilers. The object of my invention is to provide a simple construction of this type, requiring but little space, and permitting ready access to the several parts of the structure. Other features of my invention will appear from the description following hereinafter and from the accompanying drawings.

In the drawings, Fig. 1 is a partial front elevation showing my invention applied to a cylindrical boiler with two large furnace flues; Fig. 2 is a side elevation, with parts in section; Fig. 3 is a partial plan view with the steam collectors in section; Fig. 4 is an enlarged front elevation of a portion of the steam collectors, four of the connectors, and the superheater tube ends attached thereto, with parts in section; Fig. 5 is a front elevation, with parts in section, of a modification; and Fig. 6 is a horizontal section of a modification.

In Figs. 1 to 4 inclusive, connectors d' are secured to the front face of a body or casting which in this case contains three steam collectors, two of them, g' , for saturated steam, and the third, f' , for superheated steam. The collector f' is closed at its lower end, and beneath this closed end the two steam collectors g' are connected by a transverse channel g^2 (Fig. 2), so that the collectors g' and channel g^2 together form a U-shaped chamber. Each row of heating tubes b or b' of the same group contains two superheater units. Each connector d' is connected (at one side only) with two superheater units c or c' , both belonging to the same group, each connector d' having a bore or channel k' leading to the superheated steam collector f' and another channel l' communicating with the saturated steam collector g' . From each of the channels k' , l' two lateral ducts extend at right angles toward the same side, these

ducts being connected by soldering or welding with the tubular ends of the superheater units c or c' respectively. The two connectors d' belonging to like rows of adjacent groups are arranged to overlap at their adjoining ends, the connectors being of the same triangular form, but one of them having its horizontal side at the top, and the other at the bottom. The smoke box or stack h will readily receive the new superheater arrangement, without requiring to be made different in shape or size from a smoke box for a boiler having no superheater. The body or casting containing the steam collectors is secured to the boiler by brackets a' .

In Fig. 5 I have illustrated an arrangement in which only two steam collectors f , g are employed. The connectors d'' are of triangular shape, and overlapping, in a manner analogous to those of Figs. 1 to 4. It will be noted, however, that in Fig. 5 channels at the left hand (lower) portions of the two adjoining connectors communicate with the same steam collector (f), and likewise, the channels at the right hand (upper) portions of companion conductors g connect with the same steam collector (g): in Fig. 4, the channels at like ends of two companion connectors d' communicate with different steam collectors. Another difference lies in the fact that in Fig. 4 a separate fastening screw n is provided for each connector d' , whereas in Fig. 5 the same screw n serves to fasten two companion connectors d'' .

Another modification is shown in Fig. 6. The connectors d' are of the same construction as in Fig. 4, but the arrangement of the steam collectors f^2 , g^2 is somewhat different. They are formed by an inner member p and an outer member q , both substantially U-shaped in cross section and connected at the front by a vertical plate or wall r , into which screws n are fitted. The dimension of these collectors, measured from front to rear, is somewhat greater than that of the flat collectors of the examples first described above, but still considerably less than when the steam collectors are one in front of the other and have lateral connections with the superheater units.

Various modifications may be made without departing from the nature of my invention as set forth in the appended claims.

I claim:

5. 1. In a superheater arrangement for ships' cylindrical boilers having smoke flues arranged in groups separated by and at either side of an upright interval, a steam chest having an inner wall defining a central steam passage and an outer wall having a cross-sectional outline similar to that of the inner wall and surrounding and defining with said inner wall a pair of side steam passages, a wall closing all of said 10 passages, a plurality of superheater elements arranged within the smoke flues of said boilers and means to connect said superheater elements with said passages comprising a plurality of triangular shaped 15 connectors secured to said last named wall and arranged in pairs of overlapping relation, each of said connectors having a steam channel adjacent two of the apices thereof to furnish communication between said 20 superheater elements and said passages.
2. In a superheater arrangement for ships' cylindrical boilers having smoke flues arranged in groups separated by upright intervals, superheater units located in said flues, a collector for saturated steam, located in front of an interval between said groups, a collector for superheated steam, located in front of the same interval and laterally of the first mentioned collector, the combined 25 width of said collectors being no greater than the width of an interval, connectors arranged in overlapping pairs in front of, and directly connected to, said collectors and provided with ducts communicating 30 rearwardly with the respective collectors, said ducts having lateral openings connected with said superheater units both at the right and at the left of said interval, and the horizontal and vertical dimensions of 35 each assembled pair of connectors being no 40 45

greater respectively than the width of an interval and the vertical distance between adjacent rows of smoke flues.

3. In a superheater arrangement for steam boilers having smoke flues arranged in groups separated by upright intervals, superheater units located in said flues, a collector for saturated steam, located in front of an interval between said groups, a collector for superheated steam, located in front of the same interval and laterally of the first mentioned collector, the combined width of said collectors being no greater than the width of an interval, and triangular shaped connectors arranged in overlapping relationship in front of the said collectors and having separate lateral openings, one for each of end of each superheater unit of the same group, communicating with the respective collectors and superheater units, said connectors having the front faces thereof located in the same vertical plane and the horizontal and vertical dimensions of each assembled pair of connectors being no greater respectively than the width of an interval and the vertical distance between adjacent rows of smoke flues.

4. In a superheater arrangement for ships' cylindrical boilers having smoke flues arranged in groups separated by and at either side of an upright interval, a steam chest having an inner wall defining a central steam passage and an outer wall having a cross-sectional outline similar to that of the inner wall and surrounding and defining with said inner wall a pair of side steam passages, a wall closing all of said passages, a plurality of superheater elements arranged within the smoke flues of said boilers and means to connect said superheater elements with said passages.

In testimony whereof I have hereunto set my hand.

HEINRICH TOUSSAINT.
